[57] CLAIM

The ornamental design for a handle for an article of flatware, as shown and described.

DESCRIPTION

FIG. 1 is a top plan view of a handle for an article of flatware showing our new design.

FIG. 2 is a left side elevational view thereof.

FIG. 3 is a right side elevational view thereof.

FIG. 4 is a bottom plan view thereof.

FIG. 5 is a sectional view taken along line 5—5 on FIG. 1.

The broken line showing of the fork tines in FIGS. 1—4 is illustrative of environmental structure only and forms no part of the claimed design.

FIG. 2

FIG. 1

FIG. 3

FIG. 4

FIG. 5
